(57) CLAIM

We claim, the ornamental design for a portable caddy, as shown and described.

DESCRIPTION

FIG. 1 is a perspective view of a portable caddy showing our new design;

FIG. 2 is a front view thereof;

FIG. 3 is a top plan view thereof; and,

FIG. 4 is a side view thereof, the opposite side being a mirror image.

The broken lines are for illustrative purposes only and form no part of the claimed design.
